[57] CLAIM

The ornamental design for plate-like article holder, as shown and described.

DESCRIPTION

FIG. 1 is a front-top perspective view of a first embodiment of a plate-like article holder of my new design;

FIG. 2 is a rear-bottom perspective view of the plate-like article holder of FIG. 1;

FIG. 3 is a front-top perspective view of a second embodiment of the plate-like article holder of my new design showing its use in a first environment;

FIG. 4 is a rear-bottom perspective view of the plate-like article holder of FIG. 3;

FIG. 5 is a front-top perspective view of the second embodiment of the plate-like article holder showing its use in a second environment;

FIG. 6 is a rear-bottom perspective view of the plate-like article holder of FIG. 5;

FIG. 7 is a front-top perspective view of the second embodiment of the plate-like article holder showing its use in a third environment;

FIG. 8 is a rear-bottom perspective view of the plate-like article holder of FIG. 7;

FIG. 9 is a front-top perspective view of the second embodiment of the plate-like article holder showing its use in a fourth environment;

FIG. 10 is a rear-top perspective view of the plate-like article holder of FIG. 9;

FIG. 11 is a front-top perspective view of the second embodiment of the plate-like article holder showing its use in a fifth environment; and,

FIG. 12 is a rear-bottom perspective view of the plate-like article holder of FIG. 11.

The broken line showings of FIGS. 1 to 12 are for illustrative purposes only and form no part of the claimed design.

The portions of the article in the second embodiment of FIGS. 3 to 12 which are obscured in all of FIGS. 3 to 12 are not considered to be a part of the claimed invention.
